CLAIM

The ornamental design for the agrochemical bottle, as shown and described.

DESCRIPTION

FIG. 1. is a perspective view of a agrochemical bottle showing our new design;

FIG. 2. is a front elevation view thereof; the rear being a mirror image;

FIG. 3. is a top plan view;

FIG. 4. is a bottom plan view;

FIG. 5. is a right side elevational view thereof, the opposite side being a mirror image; and,

FIG. 6. is a perspective view of the agrochemical bottle with a cap attached thereto.

FIGS. 1-5. are shown without the cap attached to the agrochemical bottle.
